Philip L. Bowman, Syracuse, N.Y.

Original No. 180,389, dated June 4, 1957, Serial No. 37,755, September 2, 1955, for 14 years. Application for reissue July 17, 1957, Serial No. 46,991. Term of patent 14 years

(Cl. D30—1)

Matter enclosed in heavy brackets [ ] appears in the original patent but forms no part of this reissue specification; matter printed in italics indicates the additions made by reissue.

Figure 1 [The figure] is a side elevational view of a gun, embodying my new design.

[The opposite side of the gun is the same as the side shown.]

Figure 2 is a side elevational view of the opposite side of said gun.

I claim:

The ornamental design for a gun, as shown [and described].
